UNITED STATES PATENT OFFICE.

FREDERIC M. CARD, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

PRESSER-FOOT-LIFTING MECHANISM FOR SEWING MACHINES.

Application filed December 16, 1927. Serial No. 240,333.

This invention relates to improvements in automatic presser-foot lifting mechanisms for sewing machines and has for its object to provide a simple construction of this character, capable of being readily applied to a sewing machine in commercial use and of being readily thrown into and out of operation at will during the operation of the machine.

10 While, in principle, the present presser-foot lifting mechanism may evidently be readily embodied in sewing machines generally, it was more particularly designed for use in the commercially well-known zigzag 15 stitch sewing machine disclosed, for instance, in the U. S. patent to G. M. Eames and J. S. Finch, No. 1,196,534, August 29, 1916.

In its preferred embodiment, the improved construction comprises a lifter-lever fulcrumed intermediate its ends upon the machine frame, one arm of the lever being positioned to engage the usual projecting arm of the presser-bar lifter sleeve and the other arm of the lever carrying a roller adapted, 25 in the operative position of the lever, to be engaged by a cam mounted upon the usual needle-vibrating shaft of the machine. The two arms of the lever are connected by the links of a toggle-joint of which the knuckle 30 may be conveniently shifted in one direction to rigidly lock the lever arms against relative movement in operative position or in an opposite direction to swing the lever arms about their common fulcrum into inoperative 35 position. The fulcrum-point of the lever coincides with the point of pivotal connection of said lever arms and also coincides with the fulcrum-point of the regular treadle-controlled lifter lever for the presser-bar, while the actuating cam of the present 40 lifter-lever replaces the usual collar upon the projecting end of the needle-vibrating shaft. It will therefore be apparent that the present improvement may be readily applied to 45 any sewing machine of the class specified without any material alteration of the regular parts of the machine.

In the accompanying drawings, Fig. 1 is a rear side elevation, partly in section, of 50 a sewing machine to which the present improvement has been applied. Fig. 2 is a sectional view substantially on the line 2-2 of Fig. 1. Fig. 3 is a sectional view substantially on the line 3-3 of Fig. 1. Fig. 4 is

a perspective view of a portion of the presser-bar lifter sleeve and of the end of the lever engaging an arm of said sleeve.

Referring to the drawings, the sewing machine for which the present improvement was more particularly designed comprises a 60 base 1, from which projects the forwardly extending work-supporting arm 2. Rising from the base 1 is the usual tubular standard 3 of the overhanging bracket-arm 4, terminating in the head 5.

Journalized in the bracket-arm 4 is the rotary main shaft 6, carrying at one end the driving pulley 7 and operatively connected at its opposite end, in the usual manner, with the needle-bar 8, carrying the needle 9, (shown in dotted lines only in Fig. 1), to 70 impart vertical reciprocations to said needle. The needle-bar 8 is journalized for endwise reciprocation in suitable bearings provided in the frame 10 mounted to swing or vibrate 75 about the pivot-pin 11. The lower end of the swinging frame 10 is suitably joined to the forward end of the connecting-rod 12, of which the opposite end is provided with the fork 13 straddling the cam 14 upon the 80 transverse shaft 15, suitably journalized in the bracket-arm 4. The cam-shaft 15 carries the worm-wheel 16 driven by the worm 17 upon the main-shaft 6, the proportions of the worm and worm-wheel being such that 85 the main-shaft 6 rotates twice for each revolution of the cam-shaft.

The connecting rod 12 is, as usual, pivotally connected with one end of the link 18 of which the opposite end is fulcrumed upon 90 the crank-arm 19 fixed upon the inner end of the shaft 20 journalized in suitable bearings provided in the bracket-arm 4. To the outer end of said shaft 20 is suitably secured the adjusting arm 21 of which the free end 95 may be adjustably fixed in any selected position lengthwise of the segmental slot 22 provided in the bracket 23 upon the arm 4. Preferably the movement of the arm 21, in one direction, is limited by an adjustable 100 screw 24 upon the bracket 23. It will be understood that adjustment of the arm 21 with respect to the slot 22 moves the shaft 20 to thereby shift the fulcrum point of the link 18 afforded by the crank-arm 19. It will 105 also be understood that changes in the position of the fulcrum-point of the link 18 effect variations in the amplitude of lateral

throw of the needle 9 under the action of the cam 14 upon the connecting rod 12.

Journalized for vertical movements in suitable bearings provided in the head 5 is the 5 presser-bar 25 carrying at its lower end the presser-foot 26. Surrounding the presser-bar is the usual lifter-sleeve 27, having at its lower end the divergent arms 28 and 29, the upper end of said sleeve 27 being positioned to engage the collar 30 fixed upon the presser-bar. As usual, the arm 28 is adapted to be engaged by the hand lifter-lever 31, while the arm 29 is positioned to be engaged by a treadle operated lever.

15 The machine as hereinbefore described is commercially well known in the art and it is therefore deemed unessential to enter into greater detail in the description of its structural features.

20 Referring now more particularly to the present improvement in this machine, provision is made for at will automatically lifting the presser-foot above the work during the operation of the machine. The mechanism provided for this purpose comprises 25 two arms 32 and 33 having a coincident pivotal support upon a shouldered pivot-bolt 34 threaded into the bracket-arm 4, it being understood that the arms 32 and 33 are free to 30 swing about their common pivotal support with respect to each other. The forward end of the arm 32 adjustably carries a lifter element 35 constituting one member of an angle-bracket of which the other member 36 35 is provided with vertically aligned, elongated slots, as 37, entered by guide-screws, as 38, threaded into the arm 32. The bracket-member 36, at its upper end, has a lateral ear 39 into which is threaded an adjusting-screw 40 40 journaled in an apertured ear 41 formed on the arm 32. The lifter element 35 underlies the arm 29 of the presser-bar lifter sleeve and carries an adjustable screw 42 adapted to bear upon a shelf 43 regularly provided 45 upon the bracket-arm head 5 to thereby limit the downward movement of the free end of the arm 32.

Upon the free end of the arm 33 is journalized a flanged roller 44 engaged by a cam 50 45 having its hub 46 fixed upon the projecting end of the shaft 15, said cam 45 replacing the collar heretofore employed in this machine for holding the shaft 15 against endwise movement in its bearings. It will 55 be observed that the cam 45 has two active portions terminating in the spaced nubs 47, whereby during the operation of the machine the free end of the arm 33 is depressed twice for each rotation of the shaft, i. e., once for 60 each complete endwise reciprocation of the needle.

Means are provided for securing the arms 32 and 33, in operative position, against relative angular movement, whereby said arms 65 together constitute a lifter-lever functioning

during the operation of the machine to transmit lifting movements to the presser-bar 25, the lever-arm securing means being of a character whereby during the operation of the machine the angular relationship of the 70 arms 32 and 33 with respect to each other may be at will changed to render the lever inoperative. To this end, one member 48 of a link-toggle is pivoted by a screw 49 upon the arm 32. Connected with the member 48 75 by means of a pivot-screw 50 is the other member or link 51 of the toggle, said member 51 being pivotally connected by means of a pivot-screw 52 to a lateral extension 53 of the arm 33. For conveniently shifting 80 the toggle-knuckle constituted by the pivot-screw 50, to thereby alter the angular relationship of the arms 32 and 33, the member 48 is extended beyond the knuckle to provide the finger-piece 54 depending below the 85 bracket-arm 4, whereby said finger-piece is readily accessible to a machine operator. Furthermore, the member 48 is provided at opposite sides of the toggle-knuckle with laterally projecting stop-ears 55 and 56 in position to be alternately engaged by the link 51 to limit the movement of said toggle-knuckle in opposite directions.

It will be observed that the pivot-bolt 34 also constitutes the fulcrum of the usual 90 treadle operated lifter-lever 57, of which the laterally extending end 58 also underlies the arm 29 of the lifter sleeve. Therefore to apply the present improvement to the commercial machine herein described in general, 100 it is only necessary to substitute the pivot-bolt 34 for the lifter-lever fulcrum screw usually employed and to substitute the cam 45 for the regular shaft-collar. When the lifter device is applied to the machine and it is 105 desired to intermittently lift the presser-bar against the action of its usual depressing spring (not shown), the finger-piece 54 is manipulated to shift the toggle into the full 110 line position shown in Fig. 1, with the link 115 51 engaging the stop-ear 56. In this position, the roller 44 is disposed in engagement with the cam 45 thereby transmitting intermittent lifting movements to the presser-bar through the lever-arms 32 and 33 rigidly 120 maintained in definite angular relationship by the toggle described. When the toggle is shifted into the dotted line position shown in Fig. 1, the forward end of the arm 32 drops slightly, or until the stop-screw 42 125 engages the shelf 43. The arm 32 being held against further movement, the change in the angular relationship of the arms 32 and 33, caused by the shifting of the toggle-knuckle, withdraws the roller 44 from engagement with the cam 45 to render the lifter device inoperative.

Having thus set forth the nature of the invention, what I claim herein is:—

1. A presser-bar lifting mechanism for 130

sewing machines, including a lever comprising pivotally connected arms adapted to be rigidly maintained in a definite angular relationship, an actuating member adapted to operatively engage one of the arms of said lever, a lifter-member associated with the presser-bar of the machine adapted to be engaged by the other arm of said lever, and means for at will during the operation of the machine changing the relative angular position of said arms to render said lever inoperative to lift said presser-bar.

2. A presser-bar lifting mechanism for sewing machines, including a lever comprising pivotally connected arms adapted to be rigidly maintained in a definite angular relationship, a pivotal support for said lever coinciding with the pivotal connection of the lever-arms, an actuating member adapted to operatively engage one of the arms of said lever, a lifter-member associated with the presser-bar of the machine adapted to be engaged by the other arm of said lever, and means for at will during the operation of the machine changing the relative angular position of said arms to render said lever inoperative to lift said presser-bar.

3. A presser-bar lifting mechanism for sewing machines, including a lever comprising pivotally connected arms, a toggle-joint connection between said arms, an actuating member adapted to operatively engage one of the arms of said lever, and a lifter-member associated with the presser-bar of the machine adapted to be engaged by the other arm of said lever.

4. A presser-bar lifting mechanism for sewing machines, including a lever comprising pivotally connected arms, a toggle-joint connection between said arms, means for limiting the extent of movement of the toggle-joint knuckle, a lifter-member associated with the presser-bar of the machine

adapted to be engaged by said lever, and means for rocking said lever.

5. A presser-bar lifting mechanism for sewing machines, including a lever comprising pivotally connected arms, a toggle-joint connection between said arms, a lifter-member associated with the presser-bar of the machine adapted to be engaged by said lever, means for rocking said lever, and means for at will during the operation of the machine shifting the knuckle of said toggle-joint to change the relative angular relationship of said lever arms.

6. A presser-bar lifting mechanism for sewing machines, including a lever comprising pivotally connected arms, a toggle-joint connection between said arms, one of the link-members of said toggle-joint being extended to provide convenient means to shift the knuckle of said joint, a lifter-member associated with the presser-bar of the machine, a bracket adjustably secured upon one of the arms of said lever adapted to operatively engage said lifter-member, and a rotary cam adapted to operatively engage the other arm of said lever.

7. A presser-bar lifting mechanism for sewing machines, including a lever comprising pivotally connected arms adapted to be rigidly maintained in a definite angular relationship, a pivotal support for said lever coinciding with the pivotal connection of the lever-arms, an actuating cam adapted to operatively engage one of the arms of said lever, a lifter-member associated with the presser-bar of the machine adapted to be engaged by the other arm of said lever, and a manually actuated presser-bar lifter-lever fulcrumed upon the pivotal support of the cam-actuated lever.

In testimony whereof, I have signed my name to this specification.

FREDERIC M. CARD.
